UNITED STATES PATENT OFFICE.

ROBERT B. MORRISON, OF ROME, GEORGIA.

BRICK-KILN FURNACE.

SPECIFICATION forming part of Letters Patent No. 512,891, dated January 16, 1894.

Application filed March 22, 1893. Serial No. 467,162. (No model.)

To all whom it may concern:

Be it known that I, ROBERT B. MORRISON, a citizen of the United States, residing at Rome, in the county of Floyd and State of Georgia, have invented certain new and useful Improvements in Brick-Kilns, of which the following is a specification, reference being had therein to the accompanying drawings.

This invention relates to improvements in kilns for burning brick and similar articles, and it is designed particularly as an improvement on that class of kilns for which Letters Patent were granted to me March 9, 1886, and numbered 337,696.

15 The invention has for its object to provide means whereby a more thorough heating of the kiln is secured, and to so arrange the heating and ventilating flues that the distribution of the heat in the kiln may be regulated.

20 In the drawings:—Figure 1 is an elevation of the kiln showing the furnace in section. Fig. 2 is a horizontal sectional view on line 2—2 of Fig. 1. Fig. 3 is a longitudinal sectional view of the furnace and adjoining kiln wall; and Fig. 4 is a transverse section of the furnace on line 4—4 of Fig. 3.

Referring to the parts by letter, *a* designates the furnace; *b* the grate therein; *c* the inner arch of fire brick; *d* the outer arch of brick, and *e* the air space between the inner and outer arches. This air space begins at the base of the arch and extends entirely over it; and it extends from near the front wall of the furnace to the rear end thereof. This arch 35 may be built in any manner, though the simplest way seems to be to first build the inner arch of fire brick, then lay lengthwise over said arch a layer of boards one inch (1") high by two inches (2") wide, and then turning the 40 outer arch over the boards, and then removing the boards, leaving an air space between the arches of one inch in height. This air space is closed at its front end, and at its rear end it opens into the combustion chambers *f* 45 *f* which are formed in the kiln wall on each side of the furnace.

g is the kiln wall; *h*, *h* and *h'* are eyes formed in this wall the center eye *h'* opening at its front end directly into the furnace, and the 50 eyes *h*, *h* opening into the combustion chambers *f*.

i are two air inlet pipes which are placed

in the furnace walls near the front ends thereof. These pipes enter the furnace walls at the grate level, and extend up said walls behind the fire brick lining thereof, and then follow the curve of the arch, their upper closed ends meeting in the center thereof. These pipes are thus made and placed in the walls separately in order that they may be easily handled, and made to conform to the curvature of the arch without straining or breaking them.

j, *j* are small pipes which enter the arched portion of the main pipes *i* and extend forwardly into the air-space *e*, and conduct the inflowing air from the inlet pipes *i* into said air space.

k, *k* are the cold air inlet flues which are formed in the furnace wall proper at one side 70 of the eyes formed therein, and extend above said eyes; *l*, *l* are openings from said flues into the eyes, said openings being formed near the upper end of the eyes.

m, *m* are wall-flues which are formed on the 75 inner side of the kiln wall and extend upwardly from the top of the eyes.

n, *n* are passages leading the flues *k* at their upper ends into the wall-flues *m*, said passages being about nine feet (9') above bottom 80 of eye.

o, *o* are dampers which are placed in the flue *k* between the openings into the eyes and the passages *n*, *n*, said dampers being operated from the outside of the kiln in any suitable manner. The cold air flues *k* extend to the bottom of the kiln and are carried by horizontal passages to the outer side of the kiln, the outer ends of said passages being provided with suitable regulating valves. 90

The operation of my improved kiln is as follows:—Air is drawn into the air space *e* through the pipes *i* and small pipes *j*, and is heated to a high temperature by the hot fire-brick arch *c* and then passes rearwardly into 95 the combustion chambers and from there into the kiln through the eyes *h*. The inlet openings of the pipes *i* are placed low in the furnace walls in order to secure the proper draft to carry the hot air in the air space into the combustion chambers. It will thus be seen that a constant draft of hot air into the kiln is secured without causing said air to pass through the furnace, and that the heat of the 100

fire brick arch is utilized. Hot air from the eyes in the kiln wall is drawn up the wall-flue *m*, and when it is desired to throw all the heat from the eyes directly into the kiln, 5 the dampers *o* are opened, allowing the cold air from flues *k* to flow into the wall flues, producing a down draft therein and causing the hot air to pass directly into the kiln. The quantity of cold air admitted to these 10 flues may be regulated by the valves in their outer ends. It will also be observed that the introduction of oxygen into, and mixing it with the gases in the combustion chambers will assist free combustion of fuel.

15 The object of employing the iron pipes *i* and placing them in the solid brick work of the furnace, and connecting them by means of the small pipes *j* with the air space is to evenly distribute the inflowing air over the 20 surface of the fire brick arch and also to prevent egress of air to the air space except through the pipes *j*, which could not be conveniently done with a brick flue.

Having thus fully described my invention, 25 what I claim is—

1. A brick kiln consisting of a kiln and a furnace, said furnace having an air space, as *e*, over the arch thereof, this air space communicating at its rear end with the kiln, an 30 air-inlet flue having its lower open end below the lower end of said air-space its upper portion following the curvature of the arch and communicating with the air space at intervals throughout its curved portion, said flue being 35 located at the front end of the air-space, substantially as described.

2. A brick kiln consisting of a kiln, and a furnace connected thereto by combustion

chambers and eyes, the furnace being formed with the air space *e* which is closed at its front 40 end, its rear end communicating with the combustion chambers, air inlet pipes *i* entering the furnace wall below the air space, and on each side thereof, their upper portions following the arch of the furnace, small passages 45 communicating at intervals with the arched portion of pipes *i* and extending into the air space, substantially as described.

3. A kiln consisting of a furnace and a kiln, combustion chambers formed in the kiln wall 50 and opening into the furnace, eyes connecting the furnace and combustion chambers to the kiln, and wall flues, as *m*, formed in the inner side of the kiln wall and extending upwardly from the top of the eyes, substantially as de- 55 scribed.

4. A kiln consisting of a series of eyes leading from the heating chamber to the drying chamber, wall-flue *m* formed on the inner side of the kiln wall and extending upwardly from 60 the top of the eyes, cold air flues extending from the open air up along side of the eyes, said flues being carried above the eyes, openings from these flues into the eyes, passages leading these flues at their upper ends into the 65 flues *m*, and dampers located in the cold air flues between the openings into the eyes and their upper ends, substantially as described and for the purpose set forth.

In testimony whereof I affix my signature in 70 presence of two witnesses.

ROBERT B. MORRISON.
